Primary Examiner—Doris V. Coles*Attorney, Agent, or Firm*—Kalish & Gilster[57] **CLAIM**

The ornamental design for a fishing lure rattle, as shown and described.

DESCRIPTION

FIG. 1 is a perspective view of a fishing lure rattle showing my new design;

FIG. 2 is a top plan view thereof;

FIG. 3 is a bottom plan view thereof;

FIG. 4 is a side elevational view thereof, the opposite side being a mirror image;

FIG. 5 is a front end elevational view thereof;

FIG. 6 is a rear end elevational view thereof;

FIG. 7 is a perspective view of another embodiment of the fishing lure rattle showing my new design;

FIG. 8 is a top plan view thereof;

FIG. 9 is a bottom plan view thereof;

FIG. 10 is a side elevational view thereof, the opposite side being a mirror image;

FIG. 11 is a front end elevational view thereof; and,

FIG. 12 is a rear end elevational view thereof.

The broken line showing of environment in FIGS. 1 and 7 is for illustrative purposes only and forms no part of claimed design.
